DESIGN FOR A TIRE DISPLAY RACK

Ralph Heckman, Denver, Colo., assignor to The Gates Rubber Company, Denver, Colo., a corporation of Colorado

Application June 15, 1940, Serial No. 93,038

Term of patent 7 years

To all whom it may concern:

Be it known that I, Ralph Heckman, a citizen of the United States, residing in the city and county of Denver and State of Colorado, have invented a new, original, and ornamental Design for Tire Display Racks, of which the following is a specification, reference being had to the accompanying drawing, forming part thereof.

In the drawing:

Figure 1 is a front perspective view of the tire display rack, showing my new design; and Figure 2 is a rear enlarged fragmentary perspective view thereof.

I claim:

The ornamental design for a tire display rack,
as shown.

RALPH HECKMAN.
